UNITED STATES PATENT OFFICE

136,555

DESIGN FOR A CARPENTER'S PLANE FOR USE AS AN ATTACHMENT TO HATCHETS OR SIMILAR TOOLS

Joseph A. E. Romanoski, Huntington, N. Y.

Application June 24, 1943, Serial No. 110,519

Term of patent 14 years

To all whom it may concern:

Be it known that I, Joseph A. E. Romanoski, a citizen of the United States, residing at Huntington, in the county of Suffolk and State of New York, have invented a new, original, and ornamental Design for a Carpenter's Plane for Use as an Attachment to Hatchets or Similar Tools, of which the following is a specification, reference being had to the accompanying drawing, forming part thereof.

Figure 1 is a side elevational view of a carpenter's plane for use as an attachment to hatchets or similar tools, showing my new design.

Figure 2 is a side elevational view of the opposite side thereof,

Figure 3 is a top plan view,

Figure 4 is a front end elevational view, and

Figure 5 is a bottom plan view.

I claim:

The ornamental design for a carpenter's plane for use as an attachment to hatchets or similar tools, as shown.

JOSEPH A. E. ROMANOSKI.
